Fig. 4

Fig. 3

FIG. 1 is a perspective view of a stringed musical instrument, specifically a plucked Ukrainian Kobza of the Tambur (Tanbur) class, showing my new design;

FIG. 2 is a fragmentary perspective view showing the peghead from a different direction;

FIG. 3 is a face view; and

FIG. 4 is a left side elevational thereof.

Portions of the drawings are shaded to indicate contrast.

I claim:

The ornamental design for a stringed musical instrument, as shown and described.
